UNITED STATES PATENT OFFICE.

ARTHUR C. LA MAY, OF ROCHESTER, NEW YORK, ASSIGNOR TO ROBERT BANNARD AND THOMAS J. SWANTON, BOTH OF ROCHESTER, NEW YORK.

CURRENCY CUTTING AND SIGNING MACHINE.

1,029,199.

Specification of Letters Patent.

Patented June 11, 1912.

Application filed December 1, 1910. Serial No. 595,105.

To all whom it may concern:

Be it known that I, ARTHUR C. LA MAY, a citizen of the United States, and a resident of Rochester, in the county of Monroe and 5 State of New York, have invented a new and Improved Currency Cutting and Signing Machine, of which the following is a specification.

Bank bills are usually printed in sheets 10 of four bills each the length of the sheet being the length of the bill and the width slightly in excess of the width of four bills and this invention relates to means for severing the bills and for trimming the outer 15 edges of the outside bills in the sheet and also to means for printing upon the bills, when desired, a facsimile of the authorized signature. I prefer to provide means for printing a facsimile of either the same or 20 different signatures upon opposite corners of the severed bills and as an additional protection against counterfeiting I prefer that the signature printed in the two different places on the bill be effected by materially 25 different methods. For printing upon the bills at one place a facsimile of the authorized signature I prefer to make use of a thin sheet of metal with the signature embossed thereon and the metal comprising such plate 30 heated sufficiently to slightly scorch the paper in effecting the printing on the bills and there may be, when desired, used simultaneously an ink applied to the embossed plate by means of an inking roller and in this 35 way the ink may be carried more fully into the fiber of the paper. For printing the signatures on the bills on the other place I may make use of plain electrotypes coöperating with suitable supporting surfaces, and 40 the electrotypes may preferably be carried by segments secured to the large cutter disks while the supporting surface may be similarly secured to the smaller cutting disks. The electrotypes may be supplied with ink 45 of any suitable character from the inking roller which may preferably revolve in contact with a larger roller adapted to receive and carry a suitable quantity of the ink and from which the smaller engaging roller is 50 supplied by rolling in contact therewith. For cutting the bills I prefer to make use of a series of coöperating and adjustably supported rotary cutters and for attaching the facsimile of the proper party to the bills I 55 prefer to employ a rotating printing surface

comprising a segment of a roller and coöperating therewith a segmentally arranged support for the bill, the peripheral speed of these two members being the same.

The accompanying drawings showing a 60 preferred embodiment of my invention are as follows,—

Figure 1 is a side view of the machine. Fig. 2 is a rear view of the machine with part of the casing for inclosing the upper 65 cutters removed. Fig. 3 is a side view of the means for actuating the sheet gripping mechanism. Figs. 4 and 5 are vertical sectional views taken on the line $x-y$ of Fig. 6 showing the parts to the right and to the 70 left respectively of such line. Fig. 6 shows the means for supplying the electric current to the printing mechanism and shows a part of the left hand end of the machine with reference to Fig. 2 and in a view similar to 75 that seen in Fig. 2 but enlarged and with the parts in substantially the same relative positions as shown in Fig. 2. Fig. 7 shows in plan view a part of the table for receiving the bills before they are cut. Fig. 8 is a 80 side view of a modification of the printing and inking rollers. Fig. 9 shows, in a view similar to Fig. 6, the second printing mechanism while Fig. 10 is a side view of the parts seen in Fig. 9 showing also the other 85 features of the machine coöperating therewith. Fig. 11 shows a severed bill with two 90 signatures thereon the second signature appearing on the reverse side of the bill as indicated in dotted lines.

Similar reference characters refer to similar parts throughout the several views.

Referring to Figs. 1 to 8 inclusive of the drawings,—The frame work of my machine comprises a pair of side members A and A¹ 95 connected together by suitable brace or tie rods r and by a table T. On the table T are provided fences or guides t and t^1 to receive and hold the sheets M of bills properly aligned when stacked thereon. In these 100 frame members A and A¹ are provided bearings for the main shaft S rotated by means of a crank B¹. This shaft S is grooved peripherally, as indicated, and, is splined to receive a key or feather carried by the hub 105 c of each of the cutters C and each of such hubs is provided, as indicated in Fig. 5, with a spring actuated and pivotally supported member c¹ having corrugations on the inner surface thereof adapted to coöper- 110

ate with the grooved surface of the shaft S to permit a longitudinal adjustment of each of the cutters C on the shaft S.

Each of the cutters C is provided with an opening o through which there extends a bar D. This bar D is carried by fixed disks B having hubs b, provided with set screws for rigidly securing such disks on the shaft S and near the end thereof but just inside the frame members A and A¹.

On the shaft S there are secured a series of segments u each carried by an arm U provided with a hub having a set screw for rigidly securing the same on the shaft S.

These segments comprise the means for supporting the bills just under the printing segment with which they coöperate in the manner to be explained.

Between the disks B there extends a rod P secured to the disks B and having collars p secured thereon, each adapted to coöperate with the outer end of a spring grip member d the other end of which is secured to a block d¹ carried by the bar D whereby it will be seen that the rod P and the bar D and the grip springs d are all rotated simultaneously with the disks B and the cutters C on the shaft S together also with the printing segments u.

The shaft S carries on its extreme right hand end a spur gear L meshing with a spur gear L¹ secured on the right hand end, with reference to Fig. 2, of the upper shaft S¹ on which are rigidly secured the printing segments V by means of set screws threaded through the hubs thereof as indicated in Fig. 4. This shaft S¹ is also splined to receive keys or feathers carried by the hubs c² of the upper cutters C¹, each one of which is therefore longitudinally slidable on the shaft S¹ and is held in coöperative relation with and against the corresponding cutter C by means of a spiral spring s engaging against its hub c² at one end and against the hub v² of the corresponding printing segment V at the other end. Each of these printing segments is provided with an insulating section v¹ within and upon which is secured the thin sheet of metal v embossed with the name thereon in a series of dots as indicated in Figs. 2, 4 and 6. One end of each of these plates or sheets v is connected with one of the leading wires w, the other leading wire w¹ being similarly connected to the other end of each of the printing plates v. These wires w and w¹ extend through segmental slots therefor o¹ in the cutters C¹, to permit angular adjustment of the printing wheels V, and are secured at their left hand ends, with reference to Figs. 2 and 6, one to each of the insulating rings W and W¹ respectively, upon which bear the springs w² and w³ insulatingly supported and having the supply wires 1 and 2 connected thereto for supply-

ing current from any source of electric energy such as indicated diagrammatically by the battery Z in Fig. 6.

Refer now to Figs. 3, 4, 5 and 6.—On the insides of the frame members A and A¹, as indicated in Figs. 2, 3 and 6, are seen cams G, and on the disks B are pivotally supported bell crank levers F swinging on the pins f¹ and having each in the upper arm thereof pins f² extending toward the observer from the plane of Fig. 3 and outwardly toward the end frame pieces A and A¹ of the machine. Each of these end frame members A and A¹ also carries on its inner face a spring J segmentally formed and adapted normally to spring inwardly toward the corresponding disk B. Each of these springs J is forced outwardly toward the end plate of the machine by the corresponding pin f² as the shaft S is rotated in a clockwise direction with reference to Fig. 3. A spring f³ secured to the disk B and to the lower arm of the lever F serves to keep each of the levers F in the position shown in Fig. 3 with reference to the disk B at the left hand end of the machine with reference to Figs. 2 and 6.

The bar D has a shoulder on each of its ends and a threaded extension engaging through a suitable hole therefor in the corresponding disk B and is secured therein by means of a nut, one of which nuts is seen in Fig. 3 at d². On this bar D are secured four blocks or brackets d¹, to each of which is screwed one of the segmental gripping springs d adapted normally to spring inwardly with sufficient force to grip a sheet of bills against the coöperating collar p, above described, carried on the rod P. Each of the springs d has inserted therethrough the shouldered and threaded upper end of a bolt d² held in place therein by means of a nut on its upper end, as seen in Figs. 3 and 4, and each of these bolts d² rests at its lower end on a bar H. This bar H extends through suitable segmental slots therefor o¹ in the cutters C and also through the disks B and on the ends of such bar projecting through the slot therefor in the disks B are revolubly secured rollers h adapted to engage the cams G, while the bar H engages into suitable notches f therefor in the levers F which, when the parts are in the positions indicated in Figs. 3 and 4, tend to hold the gripping springs d outwardly, away from the coöperating gripping members p carried on the rod P, to permit the insertion of a sheet of bills thereunder.

When the parts are in the position indicated in Fig. 3 a continued rotation of the shaft S over to the right does not change the relation of the parts as the rollers h freely ride over the projections g¹ on the cams G, and the pins f² carried by the levers F force, at each successive rotation, the springs J

outwardly, but, when the parts are in the position indicated in Figs. 3 and 4 in readiness to grip the paper, a slight backward rotation over to the left of the shaft S causes the pins f^2 to engage against the right hand ends of the springs J and the levers F are thereby swung over to the right to permit the bar H to be forced inwardly or downwardly under the influence of the springs d in which the upper ends of the rod d^2 are secured. For properly guiding the bar H in the slots therefor are, secured to such bar, links h^1 articulating upon pins h^2 on the outer surfaces of the disks B.

15 The shafts S^1 and S^2 are revolvably supported in the end pieces A^2 of the upper casting of the machine which between such end pieces is conformed to engage over and cover the upper cutters C^1 and the printing segments V and this entire frame work A^2 is pivotally supported upon studs a extending outwardly through and oscillable in ears carried by the frame plates A and A^1 and is held in closed position by means of 25 thumb screws a^1 engaging in suitably threaded holes therefor in the frame pieces A and A^1 .

On the under side of the table T which may, if desired be of wood are secured a series of fingers e the curvature of which is substantially formed to the pitch line of the gears L and L^1 and also the pitch line of the cutters C and C^1 in order to support the sheets of bills which are carried thereover 35 while being cut. The parts are shown in Figs. 2, 3, 4 and 6 in readiness to grip a sheet of bills. Starting with the parts in such position the operation is as follows,— The uppermost sheet of bills from the pile 40 M thereof on the table T is forced to the right with reference to Fig. 4 so that its forward edge engages under the springs d and the shaft S by means of the crank B^1 thereon is moved backwardly or to the left with reference to Figs. 3 and 4 sufficiently to disengage the lever F from the bar H permitting such bar to drop, and the rollers h thereon to engage the portions g of the cams G, thus releasing the bolts d^2 and permitting 45 the springs d to grip the forward ends of the sheet of bills against the gripping members p on the rod P. The shaft S is then rotated over to the right a complete revolution and the sheet M is held at the 50 forward end of each bill therein by one of the springs d until the rollers h come into contact with the projections g^1 on the cams G, when the bar H is forced outwardly carrying with it the rods d^2 and the springs d, which are then forced to and held in the 55 position indicated in Figs. 3 and 4 disengaged from the bills which latter are permitted to drop into a suitable tray or receptacle M ^{1} therefor as seen in Figs. 1 and 2. This action 60 is repeated until all the bills have been 65

cut. When the rollers h are on the projections g^1 of the cams G the projections f on the levers F are held under the bar H by the springs f^3 , and support such bar in its upper position, as indicated in Fig. 3, after 70 the rollers have left the projection g^1 of the cams G and until the shaft S has been given a slight backward rotation for releasing the bar H in the manner above described.

During each rotation of the shaft S the 75 shaft S^1 makes two rotations and each printing plate v is inked from the corresponding roller k and is brought against a bill printing the signature thereon and the bill, during the printing is supported by a 80 segmental section u carried by an arm U secured on the shaft S. Each segment u and each printing segment V also may be so adjusted angularly as to vary within a reasonable range the location of the signatures 85 on the bills. The table T is provided with guides or fences t and t^1 , the former adjustable to the slight variations in the sizes of the sheets.

The inking rollers k are carried by a shaft 90 S^2 revolvably supported, as above described, and in order to maintain a proper supply of ink on the rollers k I may make use of the arrangement shown in Fig. 8 to which reference is now made. In this arrangement I 95 provide an ink carrying member K conformed to complete the wheel of which the member V carrying the printing plate v is a segment and this ink carrying member K may be impregnated with ink sufficient to 100 supply the inking roller k for a considerable length of time in the operation of the machine. It will be seen at once that the roller k is continuously rotated by contact with the segment of the printing plate v and the ink carrying member K and that while it is in contact with such ink carrying member K it receives ink therefrom which in turn is delivered to the printing segment v when in contact therewith.

Referring now to Figs. 9, 10 and 11,— For printing the second signature on the reverse side of the sheets or bills I secure to the cutters C the slotted segments U^1 by means of suitable bolts as indicated engaging through the slot in the segments U^1 . These segments U^1 carry the printing surfaces or axially extending segments u^1 adapted to coöperate with which are seen the supporting segments V^1 bolted to the upper 115 cutters C^1 . These printing segments u^1 carry the type for effecting the printing and the type on each segment are adapted to receive a suitable supply of ink, on each rotation of the shaft S, from a suitable inking 120 roller n^1 to which ink is supplied from a larger supply roller n held in contact therewith by means of a spring j secured to the fixed axis upon which the roller n revolves and operating to 125 130

draw the roller n against the roller n^1 . The roller n^1 is revolubly supported in bearings in the frame piece N while the fixed rod n^5 upon which the roller n revolves is supported at each end in a slot in this frame piece N . This frame piece N is pivotally supported at its upper left hand corner in ears n^2 extending downwardly from the plate T^2 secured to the side members A and A^1 while the table T^1 is recessed on the under side to receive the plate T^2 . Each of the frame members N is adjustably held in position by means of a thumb nut n^4 threaded on a bolt n^3 extending downwardly from the under side of the plate T^2 and above the right hand end, with reference to Fig. 10, of each frame N is seen a spring operating normally to swing the frame N downwardly to cause the roller n^1 to engage against and suitably supply the printing segments n^1 with ink.

When the printing mechanism adapted to print the signature on the reverse side of the bills m of the sheets M is made use of, as seen in Figs. 9 and 10, it is preferable to employ a table such as shown at T^1 in Fig. 10 pivotally supported upon a rod Z by means of the staples z secured therein. In the mechanism shown as arranged in Figs. 9 and 10, the signature is adapted to be printed on the same ends of the sheet but on opposite sides; any desired adjustment of the relative positions between the locations of the signatures lengthwise of the bill may be provided for by angularly adjusting the printing mechanism.

It is believed from the foregoing description that the construction and method of using my bill cutting and signature printing machine are sufficiently clear to call for no further explanation herein.

What I claim is:

1. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft, such grippers being spring actuated to normally clamp the paper between them; a fixed cam and means engaging the cam and connected to the grippers permitting the grippers to assume clamping positions at a predetermined initial gripping point in each rotation of the first shaft and operating to open the grippers at a second fixed point in each such rotation of the shaft; means for holding the grippers in their open positions independent of a continuous forward rotation of the shaft; means adapted to disengage such holding means on a movement of the shaft backward from a point slightly advanced angularly from the initial gripping position

and means for arresting a backward movement of the shaft at such initial gripping point and a series of supporting segments carried by the first shaft and coöperating therewith a series of printing segments carried by the second shaft and means for inking such printing segments. 70

2. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft, such grippers being spring actuated to normally clamp the paper between them; a fixed cam and means engaging the cam and connected to the grippers permitting the grippers to assume clamping positions at a predetermined initial gripping point in each rotation of the first shaft and operating to open the grippers at a second fixed point in each such rotation of the shaft; means for holding the grippers in their open positions independent of a continuous forward rotation of the shaft; means adapted to disengage such holding means on a movement of the shaft backward from a point slightly advanced angularly from the initial gripping position 80

and means for arresting a backward movement of the shaft at such initial gripping point; a series of supporting segments carried by the first shaft and coöperating therewith a series of printing segments carried by the second shaft and means for inking such printing segments and a source of electric energy and means for connecting the characters on the printing segments thereto for heating the characters. 90

3. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft, such grippers being spring actuated to normally clamp the paper between them; a fixed cam and means engaging the cam and connected to the grippers permitting the grippers to assume clamping positions at a predetermined initial gripping point in each rotation of the first shaft and operating to open the grippers at a second fixed point in each such rotation of the shaft; means for holding the grippers in their open positions independent of a continuous forward rotation of the shaft; means adapted to disengage such holding means on a movement of the shaft backward from a point slightly advanced angularly from the initial gripping position and means for arresting a backward movement of the shaft at such 100

110

115

120

125

130

initial gripping point; a series of printing segments carried by the first shaft and co-operating therewith; a series of supporting segments carried by the second shaft and 5 means for inking the printing segments.

4. In a device for the purpose described, two coöperating series of rotary cutters supported upon substantially parallel and revolubly supported shafts; means for 10 operatively rotating the two series of cutters at substantially the same peripheral speed; a series of pairs of relatively movable grippers carried by the first shaft, such grippers being spring actuated to normally 15 clamp the paper between them; a fixed cam and means engaging the cam and connected to the grippers permitting the grippers to assume clamping positions at a pre-determined initial gripping point in each 20 rotation of the first shaft and operating to open the grippers at a second fixed point in each such rotation of the shaft; means for holding the grippers in their open positions independent of a continuous forward 25 rotation of the shaft; means adapted to disengage such holding means on a movement of the shaft backward from a point slightly advanced angularly from the initial gripping position and means for arresting 30 a backward movement of the shaft at such initial gripping point; a series of supporting segments carried by the first shaft and coöperating therewith; a series of printing segments carried by the second shaft and 35 means for inking such printing segments; a source of electric energy and means for connecting the characters on the printing segments thereto for heating the characters; a series of printing segments carried by the 40 first shaft and coöperating therewith; a series of supporting segments carried by the second shaft and means for inking the last named printing segments.

5. In a device for the purpose described, 45 two coöperating series of rotary cutters, supported upon substantially parallel and revolubly supported shafts; means for co-operatively rotating the two series of cutters at substantially the same peripheral speed; a series of pairs of relatively movable grippers carried by the first shaft, such grippers being spring actuated to normally 50 clamp the paper between them; a fixed cam and means engaging the cam and connected 55 to the grippers permitting the grippers to assume clamping positions at a predetermined initial gripping point in each rotation of the first shaft and operating to open the grippers at a second fixed point in each 60 such rotation of the shaft; means for holding the grippers in their open positions independent of a continuous forward rotation of the shaft; means adapted to disengage 65 such holding means on a movement of the shaft backward from a point slightly

advanced angularly from the initial gripping position; means for arresting a backward movement of the shaft at such initial gripping point; means adapted to receive and aline the edges of the sheets prior to 70 the engagement thereof by the grippers and a printing mechanism adapted to engage and print upon the sheets, a series of impressions properly positioned on each individual strip to be cut therefrom. 75

6. In a device for the purpose described, two coöperating series of rotary cutters supported upon substantially parallel and revolubly supported shafts; means for co-operatively rotating the two series of cutters at substantially the same peripheral speed; a series of pairs of relatively movable grippers carried by the first shaft; means independent of a continuous forward rotation of the shaft permitting the grippers to remain in open position but operating upon a backward rotation thereof from a point slightly in advance of a pre-determined initial gripping point to force the grippers into clamping position; means 80 tending to force the grippers to open position at a predetermined point in each rotation of the shaft and a rotary printing mechanism coöperatively supported with the cutting mechanism and adapted to be 85 actuated therewith.

7. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft; means independent of a continuous forward rotation 100 of the shaft permitting the grippers to remain in open position but operating upon a backward rotation thereof from a point slightly in advance of a predetermined initial gripping point to force the grippers into 105 clamping position; means tending to force the grippers to open position at a predetermined point in each rotation of the shaft and a series of supporting segments carried by the first shaft and coöperating therewith; a series of printing segments carried by the second shaft and means for inking such 110 printing segments. 115

8. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft; means independent of a continuous forward rotation of the shaft permitting the grippers to remain in open position but operating upon a backward rotation thereof from a point slightly 120 125 130

in advance of a predetermined initial gripping point to force the grippers into clamping position; means tending to force the grippers to open position at a predetermined point in each rotation of the shaft; a series of supporting segments carried by the first shaft and coöperating therewith; a series of printing segments carried by the second shaft and means for inking such printing segments and a source of electric energy and means for connecting the characters on the printing segments thereto for heating the characters.

9. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft, means independent of a continuous forward rotation of the shaft permitting the grippers to remain in open position but operating upon a backward rotation thereof from a point slightly in advance of a predetermined initial gripping point to force the grippers into clamping position; means tending to force the grippers to open position at a predetermined point in each rotation of the shaft and a series of printing segments carried by the first shaft and coöperating therewith; a series of supporting segments carried by the second shaft and means for inking the printing segments.

10. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft; means independent of a continuous forward rotation of the shaft permitting the grippers to remain in open position but operating upon a backward rotation thereof from a point slightly in advance of a predetermined initial gripping point to force the grippers into clamping position; means tending to force the grippers to open position at a predetermined point in each rotation of the shaft and a series of printing segments carried by the second shaft and coöperating therewith; a series of supporting segments carried by the first shaft and means for inking such printing segments; a source of electric energy and means for connecting the characters on the printing segments thereto for heating the characters and a series of printing segments carried by the first shaft and coöperating therewith; a series of supporting segments carried by the second shaft and means for inking the last named printing segments.

11. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers carried by the first shaft; means independent of a continuous forward rotation of the shaft permitting the grippers to remain in open position but operating upon a backward rotation thereof from a point slightly in advance of a predetermined initial gripping point to force the grippers into clamping position; means tending to force the grippers to open position at a predetermined point in each rotation of the shaft; means adapted to receive and aline the edges of the sheets prior to the engagement thereof by the grippers and a printing mechanism adapted to engage and print upon the sheets a series of impressions properly positioned on each individual strip to be cut therefrom.

12. In a device for the purpose described, two coöperating series of rotary cutters supported upon substantially parallel and revolubly supported shafts; means for coöperatively rotating the two series of cutters at substantially the same peripheral speed; a series of relatively movable grippers carried by the first shaft, such grippers spring actuated to normally clamp the paper between them; a fixed cam and means engaging the cam and connected to the grippers permitting the grippers to assume clamping positions at a predetermined initial gripping point in each rotation of the first shaft and operating to open the grippers at a second fixed point in each such rotation of the shaft; means for holding the grippers in their open positions permitting a continuous forward rotation of the shaft; means adapted to disengage such holding means on a movement of the shaft backward from a point slightly advanced angularly from the initial gripping position and means for arresting a backward movement of the shaft at such initial gripping point; a series of supporting segments carried by the first shaft and coöperating therewith; a series of printing segments carried by the second shaft; means for inking such printing segments; a series of printing segments carried by the first shaft and coöperating therewith; a series of supporting segments carried by the second shaft and means for inking the last named printing segments.

13. In a device for the purpose described, two coöperating series of rotary cutters supported upon substantially parallel and revolubly supported shafts; means for coöperatively rotating the two series of cutters at substantially the same peripheral speed; a series of pairs of relatively movable grippers

pers carried by the first shaft; means independent of a continuous forward rotation of the shaft permitting the grippers to remain in open position but operating upon a backward rotation thereof from a point slightly in advance of a predetermined initial gripping point to force the grippers into clamping position; means tending to force the grippers to open position at a predetermined point in each rotation of the shaft; a series of supporting segments carried by the first shaft and coöperating therewith; a series of printing segments carried by the second shaft; means for inking such printing segments; a series of printing segments carried by the first shaft and coöperating therewith; a series of supporting segments carried by the second shaft and means for inking the last named segments.

14. In a device for the purpose described, two series of rotary cutters supported upon substantially parallel and revolvably sup-

ported shafts and means for rotating the cutters of both series at substantially the same peripheral speed; a gripping mechanism carried by and rotating with one series of cutters for engaging, holding and advancing the sheets one at a time through the cutters; means operating to release the grippers at the completion of the cutting operation; a printing segment located between each adjacent pair of cutters of each series, supported to revolve therewith and adapted to print upon the sheets as they are being cut; means for inking such printing segments and coöperating with each of such printing segments a supporting segment located between each corresponding adjacent pair of cutters of the other series and supported to revolve therewith.
